Patented Feb. 28, 1922.

UNITED STATES PATENT OFFICE.

ROY H. SMITH, OF KENT, OHIO.

METHOD OF MAKING TOOLS.

1,407,894.

Specification of Letters Patent. Patented Feb. 28, 1922.

Application filed October 4, 1919. Serial No. 328,500.

To all whom it may concern:

Be it known that I, ROY H. SMITH, a citizen of the United States, residing at Kent, in the county of Portage and State 5 of Ohio, have invented a certain new and useful Improvement in Methods of Making Tools, of which the following is a full, clear, and exact description.

The present invention relates to a method 10 of forming tools, particularly wrenches of the socket type, and has for its object to provide a method by which efficient tools such as socket wrenches can be produced in finished form, quickly and economically 15 with regard to time, material, and apparatus required for their production.

Further the invention aims to provide a method by which a strong and readily manipulated wrench adapted particularly for 20 setting or removing rim nuts of a demountable rim automobile wheel, may be formed inexpensively from a small straight iron bar, preferably round in cross-section.

In accordance with my invention, two 25 substantially parallel shank members which may be parts of the same rod, are subjected to the action of dies and an upsetting tool so as to form a tool head therein, and in carrying out the invention in the preferred 30 way a rod of suitable length and size is bent on itself, or doubled, and an integral tool head is formed at the closed end or at the bend between the doubled portions, which tool head, in the production of socket 35 wrenches is formed by upsetting the closed end of the doubled portion and by forming a wrench socket therein. One or both ends of the rod may be formed into handle or handles, and for a socket wrench for re-

40 moving and setting rim nuts of a demountable rim wheel, the end portions of the rod are preferably extended laterally from the doubled portion which forms the shank of the wrench so as to provide oppositely projecting handle portions which can be given any shape or bends desired to best adapt 45 it for the purpose.

The invention may be briefly summarized 50 as consisting in the steps of the improved method which will be described in the specification and set forth in the appended claims.

One form of the wrench and one way of

carrying out the method are illustrated in the accompanying sheet of drawings, 55 wherein Fig. 1 is a side view of a bar after being bent in accordance with the first step of the process to form a doubled middle portion designed to be formed into the shank and socketed head, and the single 60 laterally projecting handle portions; Fig. 2 shows the second step of the process wherein the head is upset onto the end of the doubled shank portion; Fig. 3 is a view showing the third and final step of the 65 process wherein the socket is formed in the upset end or head; Fig. 4 is a perspective view of the completed wrench, part of one handle being broken away; and Figs. 5 and 6 are sectional views substantially 70 along the lines 5—5 and 6—6 of Figs. 1 and 4 respectively. Fig. 7 is a view similar to Fig. 2 on a reduced scale showing a slight modification.

In carrying out my invention in the way 75 that I now regard as the most satisfactory and efficient, I start with a suitable length of a straight bar of iron, steel or other suitable metal, preferably round in cross-section, and this bar is bent preferably in the cold, sub- 80 stantially in the form shown in Fig. 1 so as to form a doubled middle portion 10, and single laterally or oppositely extending handle or manipulating portions 11. In other words, the bar is formed in the shape of a 85 T, with a double shank 10 which is to form the shank and socketed head of the wrench.

Then the doubled portion 10 is heated to a welding or upsetting heat, and the heated doubled portion is gripped between a pair of 90 dies such as illustrated at 12 and 13, with the end of the shank portion 10 projecting beyond the dies, and then the projecting doubled end of the shank portion 10 is struck by a suitable upsetting tool such as 95 shown at 14, so as to form a solid annular head shown at 15 in Fig. 3.

When the dies 12 and 13 grip the doubled portion 10, sufficient pressure is preferably exerted to weld the two parts or members 100 of the shank portion together into a substantially continuous unitary piece from the free doubled end of the shank to a point adjacent the point of divergence of the handle portions.

Then the work is placed between dies 16

and 17, or between different portions of the same dies as used in the step illustrated in Fig. 2, with the head 15 formed on the shank of the work set into a recess indicated 5 at 18, and then the head 15 while thus wholly enclosed in the dies, is struck with a socket forming tool 19 which imparts a hexagonal, square, or other suitable shaped socket in the head, this tool being preferably 10 provided with an annular shoulder portion 20 which enters the recess 18 and gives a finish to the end of the socketed head 15.

This forms a complete finished wrench such as illustrated in Fig. 4, with a socketed 15 head 21 consisting of a continuous solid piece integral with the parts which heretofore constituted the halves or legs of the double shank portion 10, and the latter integrally united, if desired, substantially to 20 the handles 11, though it is not necessary that these parts be welded together for any considerable extent beyond the socketed head 21.

If desired, one of the handles 11 may be 25 provided with a tapered screw-driver end 22, and the other handle may have its free end portion bent at right angles to, or substantially parallel to the shank to facilitate the rapid turning of the wrench. The last 30 mentioned features are, however, immaterial to the present invention.

Above I have described what I regard as the best embodiment of my invention, but I do not wish to be confined to the precise 35 steps explained, for it might be possible to deviate from the same to some extent without departing from the invention in its broadest aspects. For example, I have considered using two rods instead of a single 40 rod bent upon itself. These rods could be substantially L-shaped, and in producing a tool from them they would be arranged so that portions of the rods would be held side by side or in parallelism to form the shank 45 of the tool, and the other portions extended to form the handles, and in such case the two shank portions after being heated, would be gripped in the dies to weld them together, and the tool head would be upset on the 50 parallel end portions which project from the dies. This I have illustrated on a reduced scale in Fig. 7, wherein I have shown the dies as in Fig. 2, and the two rods at 23 and 24 mounted in the dies 12 and 13 as in 55 the preceding views. I do not regard this method as efficient or satisfactory as the preferred method first described.

Though my invention is especially adapted for the production of socket wrenches, it 60 might be used to advantage in forming other tools.

Having described my invention, I claim—

1. The method of making tools which comprises forming a tool head on two sub-

stantially parallel adjacent portions of metal 65 stock from which the tool is to be formed and forming a handle integral with said stock.

2. The method of forming tools which 70 comprises upsetting a portion of two substantially parallel parts of metal stock from which the shank of the tool is to be formed so as to form a tool head integral with both parts and forming portions of both parts into a handle. 75

3. The method of forming a tool which 80 comprises welding together two substantially parallel parts, and upsetting a portion thereof to form a tool head.

4. The method of making tools which 85 comprises bending a rod so as to provide a doubled portion, upsetting and forming a tool head at the closed end of the doubled portion and welding together the adjacent portions of the rod beyond the upset portion. 90

5. The method of making tools which 95 comprises bending a rod so as to form a doubled portion with a handle at one end thereof, and upsetting the opposite end thereof and forming a tool head thereon. 99

6. The method of making tools which comprises bending a rod so as to form two substantially parallel portions, welding said portions together and forming an integral tool head at the closed or bent end of said 95 portions.

7. The method of making tools which 100 comprises bending a rod so as to form laterally extended end portions and a shank formed by doubling the intermediate or middle portion of the rod upon itself, upsetting the closed bent end of the portion forming the shank, and forming a tool head thereon.

8. The method of making tools which 105 comprises bending a rod so that a portion between the ends of the rod is doubled upon itself to form a doubled shank and so that the ends of the rod extend singly in opposite directions from one end of the shank so as to form handles, and forming an integral tool head at the closed end of the shank. 110

9. The method of making a socket wrench which comprises bending a rod so as to form a doubled shank portion, upsetting a head on the closed end of the shank portion and 115 forming a wrench socket in the upset portion.

10. The method of making a socket wrench which comprises bending a rod so as to form laterally extending handles and an 120 intermediate doubled portion, with one end closed at the bend of the rod, upsetting the closed end and forming a wrench socket in the upset portion.

11. The method of making a socket 125 wrench which comprises bending a rod upon itself so as to form a doubled shank, welding together the portions forming the shank,

upsetting the closed or bent end of the shank and forming a wrench socket in the upset portion.

12. The method of forming a socket wrench which comprises bending a rod by doubling an intermediate portion of the rod upon itself so as to form a doubled shank, bending the ends so as to form single later-

ally projecting handles, welding the two portions of the shank together, and upsetting the closed end of the shank, and forming a wrench socket in the upset portion.

In testimony whereof, I hereunto affix my signature.

ROY H. SMITH.
